WRINGER CONTROL MECHANISM

Alpheus W. Altorfer, East Peoria, Ill.

Application November 26, 1934, Serial No. 754,733

3 Claims. (Cl. 192—35)

This invention relates to wringer control mechanism, particularly to a mechanism for controlling reverse mechanism for wringer rolls.

An object of the invention is to provide reverse mechanism which is power operated.

Another object is to provide power operated reverse mechanism in which the power means is manually controlled.

A further object is to provide power operated reverse mechanism in which the power means is manually controlled, the manual control means being so arranged that reversing operation of the wringer rolls is accomplished by a slight pressure of the finger.

An additional object is to provide a wringer mechanism having manually controlled power operated clutching mechanism disposed between the power source driving the wringer and the mechanism of the wringer whereby power to drive the wringer mechanism is controlled to start and stop the wringer, and an additional manually controlled power operated clutching mechanism for distributing power delivered through the first mentioned clutch mechanism whereby the direction of rotation of the wringer rolls is manually controlled.

Additional objects will become apparent in the following description and accompanying drawings in which:

Fig. 1 is a side elevational view of a wringer mechanism embodying my invention with portions of the housing broken away to expose underlying mechanism;

Fig. 2 is a fragmental sectional side elevational view showing mechanism in detail to facilitate description;

Fig. 3 is a view similar to Fig. 2 showing certain parts in operated position as will be explained;

Fig. 4 is a sectional plan view taken on line 4—4 in Fig. 3;

Fig. 5 is a sectional plan view similar to Fig. 4 showing certain parts in operated position to be explained, and

Fig. 6 is a sectional plan view taken on line 6—6 in Fig. 3.

Fig. 1 discloses my invention as embodied in a roll wringer mechanism 10, including a wringer frame 11, lower and upper rolls 12 and 13, and a wringer head mechanism disposed within a housing 14, the whole being mounted upon a support 15.

The support means, being conventional, is not shown and will not be described further than to say that a drive shaft, as will later appear, is

disposed therein whereby power for operating the wringer mechanism is made available.

Exterior of the wringer head mechanism there is disposed for convenient access, a finger key 16 having operable connection with the driven mechanism as will be explained, and a finger button 17 having operable connection, also to be explained, with the reverse mechanism of the wringer.

10 Figs. 2 and 3 illustrate that rolls 12 and 13 are mounted in the frame 11 in bearing blocks 18 and 19, block 18 being stationarily mounted while block 19 is movably mounted. A conventional spring mechanism 20 urges roll 13 toward roll 12 whereby resilient pressure relation therebetween is maintained.

The lower roll 12 has a shaft 21 extending through block 18 which has a flattened end portion 22 engaged within a collar 23, which latter is secured upon a shaft 24 journaled in a bearing 25 formed in housing 14.

Keyed to shaft 24 is a pinion 26 meshed with which is a pinion 27 keyed to a rearwardly extending boss portion 28 of a bevel gear 29. Gear 29 is supported by means of boss 28 being journaled in a bearing 30 formed in housing 14.

Gear 29 is meshed with upper and lower bevel pinions 30 and 31. The latter pinions are rotatably mounted upon a vertical shaft 33 having its upper end journaled in a bearing 34 and its lower end secured within a collar 35 which, in turn, is journaled in a bearing 36 formed in housing 14.

The lower end of collar 35 is provided with dentures 37, for a purpose to be described, and within the lower part of this collar is journaled the upper end of a drive shaft 38.

At a lower point, drive shaft 38 is journaled at 39 in a portion of housing 14, and the shaft extends downwardly to have connection with a source of power, not shown.

Shaft 38 is provided with an attached collar 40 which rests upon the surface of a floor portion of housing 14 and the lower end of shaft 33 rests upon the upper end thereof within the collar 35. Thus downward longitudinal movement of shaft 33 is prevented. Upward longitudinal movement of the shaft is obviously prevented by abutment with the bottom of bearing 34.

Pinions 30 and 31 are provided with dentures 30' and 31' and a clutch member 41, having complementary dentures extending from either end, is slidably disposed on shaft 33 between the pinions.

Clutch 41 is held in slidably keyed relation with shaft 33 by means of a key 42 secured in the shaft

and made slideable in a groove in the clutch body.

It will be apparent that, with shaft 33 rotating, clutch 41 may be slid upwardly, as in Fig. 2, to engage pinion 30 to rotate the pinion in unison with the shaft, to rotate gear 29 in a certain direction to rotate lower roll 12 in a corresponding predetermined direction. Rotation of the roll in opposite direction may obviously be accomplished by disposal of the clutch member in engagement with pinion 31 as in Fig. 3.

To accomplish the described movement of clutch 41 I provide a novel manually controlled, power operated clutch mechanism as follows:

Disposed above pinion 30, and affixed to shaft 33 is a collar member 43 having a flange portion 43', see Fig. 4, at its upper end. The flange portion is provided with dentures 44, the purpose of which will be explained shortly.

Rotatably mounted upon collar 43 is a member 45 having a cam groove 46, which follows an irregular line about the periphery of the member.

The line of the groove is indicated in dotted lines in Figs. 2 and 3, and in full line in Fig. 1.

It will be noted that the conformity of the groove is such that when the member is disposed as in Fig. 2 the groove, on the right hand side, is in a high position. Fig. 3 shows the member 45 having been rotated through 180 degrees whereby the low portion is disposed at the right. The cam groove 46 is so designed that a half-revolution thereof will shift the clutch elements from a forward position to the reverse position and the next succeeding half-revolution will return the clutch elements from the reverse position to the forward position, thus the member 45 and the groove 46 constitute a "half-revolution" cam to move the driving clutch element into engagement with either of the driven clutch elements.

Disposed in the groove is an angulated extension 47, see Fig. 6, of a member 48, which has a lower inwardly diverted portion 49. The body of member 48 is made longitudinally slideable in a vertical groove 50 in housing 14. Obviously with portion 47 engaged as shown in groove 46, rotation of member 45 will bring about reciprocal movement of member 48.

Disposed inwardly of an adjacent member 48 is a member 51 having an inwardly directed lower portion 52 which is engaged in an annular groove 53 of clutch 41.

Member 51 is so fashioned as to have portions 54, see Figs. 1, 2, and 6, extending upwardly upon both sides of member 48 and the body thereof is slidably mounted in a grooved portion 55 of housing 14.

The above described arrangement provides that member 48 is movable with respect to member 51 and that member 51 is movable to bring about sliding movement of clutch 41 for the purpose already noted.

To connect members 48 and 51 in a resilient relation I provide a bracket member 56 secured transversely of extending portions 54, the same having a downwardly extending portion 57. The portion 57 is arranged to pass through an opening in portion 49 of member 48 and through an aligned opening in portion 52 of member 51. Portion 57 obviously serves as a retainer for springs 58 disposed above and below portion 52 in such a manner as to normally hold member 51 in predetermined position with respect to member 48.

The described connection between members 48 and 51 obviously provides a means whereby re-

ciprocal movement of member 48 is transmitted to member 51, to bring about corresponding sliding movement of clutch 41. The arrangement further provides a connection whereby member 48 may move independently of member 51 in case, at the instant of operation, the dentures of clutch 41 engage upon the top of the dentures 30' or 31' and the clutch is thereby momentarily prevented from moving in unison with member 48. In practical use, the condition noted would prevail for but a moment, as continued rotation of clutch 41 would immediately bring the dentures into a position of proper register, at which time one of springs 58 would become effective to complete movement of the clutch into properly engaged position.

The drawings illustrate that member 45 has a relatively broad, flat top surface. Reference to Figs. 4 and 5 will disclose that a pawl member 59 is pivotally attached at 60 upon this top surface. The pawl has a tooth portion adapted to engage dentures 44 of collar 43 and is urged thereto by a spring 61 anchored at 62 on the top surface of member 45.

Figs. 1, 2 and 4 illustrate a bifurcated member 63 having arms extending upon either side of flange portion 43. The arms are spaced away from the top surface of member 45 a sufficient distance to permit the mechanism of pawl 59 to pass clear of the arms, and the arms are provided with downwardly directed portions 64 which normally lie in the path of the pawl.

Member 63 is provided with upstanding portions 65. By means of these, and a pin 66 supported in housing 14, member 63 is rockably supported in such a manner that it may be disposed as shown in solid lines in Fig. 3 to place portions 64 in the path of pawl 59, or moved to the position shown in dotted lines to withdraw portions 64 out of the path of the pawl.

To accomplish the movement described I provide the push button 17, already referred to.

The button is provided with a central depending portion 67 engaging the outer end of member 63 as shown. A spring 68 urges the button toward a normally elevated position.

It is to be noted that member 45 is provided with a friction device consisting of a plug 69, movably retained in an opening in the body of the member. The plug is urged into frictional contact with the surface of collar 43 by a spring 70 which is abutted by a cap screw 71. The purpose of this device is to slightly urge member 45 to rotate in unison with collar 43 and to prevent loose motion of member 45 as well as to promote quiet running.

Member 63 is normally disposed as indicated in solid lines in Fig. 2 wherein the portions 64 of member 63 lie in the path of pawl 59. This position corresponds to the position of parts shown in Fig. 5 wherein, assuming shaft 33 and dentures 44 to be in rotation in direction of the arrow, the free end of the pawl is abutted by one of portions 64, and by reason of momentarily continued rotation of member 45 the pawl is forced outwardly to the position shown.

It will be apparent that a slight, momentary manual pressure on button 17 will result in withdrawal of portions 64, as shown in dotted lines, out of the path of pawl 59, whereby the pawl is left free to engage one of dentures 44 and establish driving connection between shaft 33 and member 45.

Assuming that button 17 has been depressed only for a time sufficient to allow pawl 59 to

escape, and has then been released to permit member 63 to return to normal position, it will be apparent that the pawl will remain in engagement with a denture 44 until it shall again engage one of portions 64, which engagement will result in replacement of the pawl in disengaged position as described. From an examination of the drawings (Figs. 4 and 5) it will be seen that there are two portions 64 positioned on opposite sides of the axis of the shaft so that when one of these portions is engaged by the pawl 59 the cam structure will come to rest in forward position while if the pawl 59 is engaged by the opposite portion 64, the cam structure will come to rest in the reverse position. This arrangement constitutes a "half-revolution" clutch since whenever the button 17 is momentarily depressed and quickly released, the clutch will operate to rotate the cam member through one-half of a revolution of movement to shift the cam from a reverse to a forward position or vice versa.

It is assumed that cam groove 46 has its upper and lower positions arranged, with respect to arrestment positions of member 48, so that arrestment takes place at the points where cam groove 46 is positioned to place member 48 in its highest or lowermost positions, whereby clutch 41 will be placed in engagement with either gear 38 or 31.

It will now become apparent that, with shaft 33 rotating, wringer roll 12 may be caused to rotate alternately in opposite directions by successive momentary manipulations of button 17, and that with the wringer rolls rotating in a forward direction, as in normal use, they may be immediately reversed by simple manipulation of button 17. Restoration of normal rotation is obviously brought about by another similar movement of the button.

It is to be particularly noted in connection with the above described device that in all cases member 45 is rotated, and clutch 41 is operated, by power provided through shaft 33. The manual effort required to bring about operation of the clutch is only that necessary to overcome the pressure of spring 88 and this may obviously be very slight. Thus the reversing function of the mechanism may be accomplished by means of a slight pressure of the finger tip on button 17.

Power for operating the mechanism is provided through shaft 33 as already noted. Power is transmitted from shaft 39 to shaft 33 through a mechanism which is not a necessary part of the present invention and which has been disclosed in several patents and application for patent filed by me—particularly Letters Patent #1,868,343 issued July 19, 1932.

The mechanism herein illustrated differs from that shown in the above patent only in minor details of structure.

It is therefore thought unnecessary to describe the presently illustrated structure further than to say that a clutch member 72 is slidably keyed upon shaft 38, and has dentures 73 formed upon its upper edge which are engageable with dentures 81 formed in the lower end of collar 35.

It will be apparent that clutch 72 may be slid upwardly to engage dentures 73 and 81 to transmit rotation of shaft 38 to shaft 33 or may rest in lowered position to leave the wringer rolls motionless.

Clutch 72 is urged upwardly by a spring 76 and

to actuate the same downwardly in opposition to the spring I provide an angulated member 78 having an inwardly directed upper portion 77 engaging an annular groove 78 in clutch 72 and a lower portion 79 resting upon the under surface of a cam member 80. Member 78 is supported in vertically movable manner by means of a stud 76 slidably retained in a recess formed in structure 14. Cam 80 is rotatably mounted upon the collar member 40 which has a dentured portion 82 formed in its upper end and is secured to shaft 38 as already noted.

Cam 80 and collar 40 are similar in function to cam groove 46 and collar 43. The mechanism for operating cam 80, to rotate it through 180 degree movements, is designated 83 and is similar in function to pawl member 59. A slideable pin member 84, connected through a lever 85 with the finger key 16, functions in a manner similar to member 63 to bring about actuation of the clutch 72 to start and stop the wringer, the latter action being obviously controlled by manipulation of finger key 16.

Numerous modifications of the structure of my invention are possible without alteration of the principle thereof. I do not wish to be limited in structure or principle except within the scope of the appended claims.

What I claim is:

1. The combination in a wringer roll reversing mechanism, of a driving clutch element and a pair of driven clutch elements, and means associated with said driving clutch element for applying power thereto to throw said driving clutch element into engagement with either of said driven clutch elements or out of engagement therewith, said means being characterized by an intermittent-motion half-revolution cam, a pawl adapted to rotate said cam, a multiplicity of teeth on said driving shaft adapted to engage said pawl, a pair of stops arranged to disengage said pawl from said teeth, and a manual trip for said stops to permit reengagement of the pawl.

2. The combination in a wringer roll reversing mechanism, of a driving clutch element and a pair of driven clutch elements, and means associated with said driving clutch element for applying power thereto to throw said driving clutch element into engagement with either of said driven clutch elements or out of engagement therewith, said means being characterized by a single manually operable control and a half-revolution clutch, said half-revolution clutch being coupled to said driving clutch element to shift said driving clutch element alternately from either one of said pair of driven clutch elements to the other, responsive to successively repeated actuations of the aforementioned single manually operable control.

3. The combination in a wringer roll reversing mechanism, of a driving clutch element and a pair of driven clutch elements, and means associated with said driving clutch element for applying power thereto to throw said driving clutch element into engagement with either of said driven clutch elements or out of engagement therewith, said means being characterized by a reciprocating shifting member, a pair of stops to interrupt the movement of said shifting member at each end of its stroke, and a single manual control to release each of said stops.

ALPHUS W. ALTORFER.
